FLUSH TANK VALVE

Yervant H. Kurkjian, Clifton, N. J.

Application December 2, 1949, Serial No. 130,742

5 Claims. (Cl. 4—56)

1

This invention relates to flush tank valves, and has for one of its objects the production of a simple and efficient flush tank valve which is so constructed as to prevent the valve from being improperly seated upon the valve seat, and which is provided with means to hold the rubber portion of the valve away from the valve seat until the valve is in a proper seating position.

A further object of this invention is the production of a simple and efficient flush tank valve having means for forcing the valve into sealing engagement with a valve seat when the valve moves to a closed position, and for breaking its sealing engagement with the valve seat when a lifting pressure is exerted upon the valve stem of the valve.

A still further object of this invention is the provision of a flexible stem and connection thereof with the valve to provide for a universal movement of the valve, while seating to insure centering of the valve and the proper seating of the valve, even though the actuating rod is out of alignment or off center.

Other objects and advantages of the present invention will appear throughout the following specification and claims.

In the drawing:

Figure 1 is a side elevational view of the valve; Figure 2 is a top plan view of the valve;

Figure 3 is a vertical sectional view of the valve in its seat-sealing position upon the valve seat;

Figure 4 is a top plan view of the rigid flange ring which is carried by the lower open end of the flexible valve, a portion of the ring being shown in section;

Figure 5 is a horizontal sectional view taken on line 5—5 of Figure 1;

Figure 6 is a vertical sectional view of the valve, partly in elevation, showing the valve in a position just before it is drawn to a sealed seat-engaging position;

Figure 7 is a view similar to Figure 6 showing the manner of breaking the sealing engagement of the flexible valve with the valve seat;

Figure 8 is a fragmentary sectional view of a modified type of valve and rigid flange ring.

By referring to the drawing in detail, it will be seen that 10 designates a conventional valve seat of a conventional flush tank. A hollow flush valve 11 is adapted to fit snugly upon the seat 10, in the manner shown in the drawing. The flush valve 11 is formed of soft rubber, and is provided with an open bottom having an inturned annular flange 12 at the periphery of the open bottom. The valve 11 comprises an inverted conical body

2

having an annular thickened flange 13 around its top periphery, which flange 13 encircles a flexible diaphragm top wall 14. This diaphragm top wall 14 supports a stem 15 which preferably is provided with a socket 16 at its lower end adjacent to the point where the stem 15 connects to the diaphragm to add flexibility at this point of junction. An internally threaded socket member 17 is fitted in the upper end of the stem 15 and receives the lower threaded terminal of the valve operating rod 18, as shown in Figure 3.

Triangularly shaped ribs 19 arranged in radiating relation to the socket 16 are formed integral with the side wall 20, and the under face of the diaphragm top wall 14, as shown in Figure 3. It should be noted that since the wall 20 and the diaphragm top wall 14 are formed of flexible soft rubber, the ribs 19 will efficiently brace the same and tend to hold the body of the valve in shape and against collapse. The ribs 19 extend on an incline from a valve seat engaging portion of the side wall 20 to a point adjacent the junction of the stem 15 with the diaphragm 14, as shown clearly in Figures 3, 6 and 7.

Because of the flexible nature of the flush valve, the side wall 20 will conform to the contour of the valve seat and thereby provide an efficient seal when the valve is seated in position.

A rigid flange ring 21 formed of metal, plastic, or other rigid material, is removably secured to the inturned flange 12 of the valve 11, and comprises an inner flange 22 which overhangs the flange 12 of the valve 11, and a spaced outer flaring flange 23 which underlies the flange 12, thereby defining an annular channel between the flanges 22 and 23 to snugly retain the flexible soft rubber inturned flange 12 of the valve 11, and to hold the ring 21 upon the valve 11. The flange 23 preferably is provided with a straight horizontal upper face 24 which projects laterally and annularly at substantially right-angles to the axis of the ring 21 beyond the lower end of the valve 11. The ring 21 is provided with a central aperture 25 and an upwardly and outwardly inclined bottom face 26, as shown in detail in Figure 3.

It should be noted that the ring 21 flares outwardly or laterally of the inwardly inclined flexible wall 20 of the valve 11 so that the outer periphery of the flange 23 will contact the inner face of the outlet pipe 27 when the valve 11 is moving to a seating position upon the valve seat 10. In this way the valve will not become improperly seated upon the valve seat which might cause a leaking action, but the metal or rigid ring, by striking the valve seat or the inner face

of the outlet pipe tends to center the valve and cause the valve to be directed to a proper sealing position upon the seat 10. The force of the water hitting the upper face 24 of the flange 23 will suddenly pull the valve 11 to a proper and tight seating contact upon the valve seat. This ring 21 reinforces the lower end of the valve to prevent the valve from collapsing, and tends to hold the soft rubber valve out of closing contact with the seat until the valve is properly centered and is then suddenly and forcibly pulled to a sealing position upon the valve seat 10. Furthermore, the ring by being formed of metal, plastic, or other rigid material, and because of its inclined under face striking the metal outlet pipe 27 will tend to slide off the upper edge of the valve seat 10 toward a centered position in the outlet pipe 27 as the valve 11 moves to a closing position. It should be noted that the ring 23 causes the valve 11 to first center and to then suddenly pull the valve 11 to a sealing position upon the seat 10 when the rushing water from the tank passes downwardly through the outlet pipe 27. Furthermore, the pressure of the water upon the diaphragm top wall 14 will force the ribs 19 downwardly and thereby force the inclined wall 23 firmly in contact with the seat 10, as shown in Figure 3.

However, when the rod 18 is pulled upwardly to flush the tank, the stem 15 will be pulled upwardly, thereby raising the diaphragm 14 and in this way exerting an upward pull upon the radiating ribs 19. This upward pull upon the ribs 19 will exert an inward pull upon the valve seat engaging portion of the wall 20 to produce dimples 28 in the outer face of the wall 20 and thereby break the seal between the wall 20 and the seat 10. This action will permit water from the tank T to pass between the valve 11 and the seat 10, and thereby cause the valve to be easily released from the seat 10 without excessive pull upon the operating rod 18. Furthermore, the flexible stem and diaphragm will facilitate the centering of the valve even if the actuating rod is out of alignment or is off center. The flange 13 by extending above the diaphragm 14 defines a dished upper end for the valve to receive water from the tank and to thereby add additional weight to the valve to facilitate seating. The flexible stem and diaphragm facilitate universal movement of the valve relative to the actuating rod and irrespective of the aligned position of the actuating rod.

The ring 21 in addition to reinforcing the bottom of the valve 11 provides a weighted bottom for the valve to further facilitate the seating of the valve 11.

As shown in Figure 8, the open end of the valve 11^a may be reinforced by an encasing rigid substantially U-shaped rigid reinforcing and guiding ring 21^a, if desired, as a modified form in place of the preferred ring 21 shown in detail in Figure 3. Other detail changes in structural design may be made within the scope of the present invention, so long as these changes fall within the scope of the appended claims.

Having described the invention, what I claim as new is:

1. A tank valve comprising a hollow flexible body adapted to snugly fit upon a valve seat, said body having a substantially inverted cone-shaped formation, said body having an open lower end, a rigid ring secured to and carried by said open lower end, said ring completely surrounding the lower end of the body, and said ring

having a laterally extending flange protruding beyond the lower end of the body and adapted to contact the outlet pipe of a flush tank to hold the flexible valve out of contact with the valve seat until the valve is properly centered and is in a proper seating position.

2. A tank valve comprising a hollow flexible body, a valve seat adapted to receive said body, said body having a substantially inverted cone-shaped formation, said body having an open lower end, a rigid ring removably secured and fitted in said open lower end, said ring having a laterally extending guiding flange protruding beyond and completely surrounding the lower end of the body, said ring having a tapered upwardly and outwardly flared bottom face for facilitating the guiding of the body to a valve seat engaging position, and said ring having a straight upper face at substantial right-angles to the central axis of the body to define a water abutment face to facilitate seating of the valve as water rushes over the valve while passing through an outlet pipe upon which the valve is adapted to be used.

3. A tank valve comprising a substantially inverted cone-shaped flexible body adapted to seat snugly upon a valve seat, said body having a flexible side wall, said side wall having a valve seat engaging portion, a flexible diaphragm forming a part of the body, ribs connected to the diaphragm and connected directly inwardly and in line with said valve seat engaging portion of said side wall, actuating means connected to the diaphragm to lift the valve from a valve seat, and said diaphragm adapted to flex outwardly as said actuating means is lifted to pull said ribs and said valve seat engaging portion of said side wall inwardly of the body thereby defining depressed dimples in the outer face of the side wall of the body and to thereby break the grip of said side wall of the body from a valve seat and to thereby facilitate the moving of the valve to an open position relative to a valve seat.

4. A tank valve comprising a hollow flexible body adapted to seat snugly upon an outwardly flared valve seat of a flush tank, said body having a substantially inverted cone-shaped formation, a flexible diaphragm carried by the body, an actuating member carried by said flexible diaphragm, said body having a flexible valve seat engaging portion to provide a sealing seat engaging means for said valve, and ribs connected to said diaphragm and also connected directly in the rear of said valve seat engaging portion of said body for exerting a direct inward pulling action upon said valve seat engaging portion to pull the valve seat engaging portion away from a valve seat to break the sealing engagement thereof and to thereby release the valve from the valve seat of a flush tank.

5. A tank valve comprising a hollow flexible body adapted to seat snugly upon a complementary valve seat, said body having a substantially inverted cone-shaped formation and having a lower ring receiving end, a flexible diaphragm carried by the body, an actuating member carried by said flexible diaphragm, said body having a sealing seat engaging portion to provide a sealing seat engaging means for said valve upon a valve seat, radiating ribs connected to said diaphragm and also connected directly in the rear of said valve seat engaging portion of said body for exerting a direct pulling action upon said valve seat engaging portion to pull the valve seat engaging portion away from a valve seat to break the sealing engagement thereof and to thereby

release the valve from a valve seat, a rigid ring secured to and carried by the lower end of said body, said ring completely surrounding the lower end of said body, and said ring having a laterally extending flange protruding beyond the lower end 5 of the body and adapted to contact the outlet pipe of a flush tank to hold the flexible valve out of contact with a valve seat adapted to receive the same until the valve is properly centered and is in a proper seating position.
